LOAD BINDER

Leo Haubert, Tulsa, Okla.

Application June 6, 1946, Serial No. 674,864

3 Claims. (Cl. 254—78)

1

This invention relates to load binders, and its primary object is to improve the construction and operation of the load binders disclosed in my Patent No. 2,157,451 dated May 9, 1938. In accordance with the invention, the particular improvements are (1) a change in the shape of the drum around which the chain or cable is wrapped when the load binder is tightened, so that a greater and more uniform take-up is obtained; (2) a change in the shape of the rockers; (3) eliminating the ears 19 of the patent and changing the position of the pin which attaches the chain or cable to the drum, thereby making it unlikely that loose material will get in between the chain-attaching means and the clevis; (4) eliminating the chain-engaging teeth 26 and the ridges 22 and depressions 23 of the patent, in order to make manufacture of the drum much easier; (5) changing the form of the flanges on the drum so as to guide the chain and obviate climbing of the chain on the edges of the flanges; (6) a change in the locking means, thereby simplifying the construction of the drum and eliminating any undue strain on the locking pin, and preventing movement of the lever toward locking position.

The invention further has all the stated objects and practically all the advantages of the patented load binder, which it will be unnecessary to explain.

A further advantage of this improved load binder is that the drum and chain assembly is heavy enough to hold the load binder in open position when used vertically. All the operator need do then is to take hold of the hook on the clevis assembly and by reaching up he can hook the load binder to the chain at a point as high as he can reach without danger of the lever falling on his head, as is likely to happen with the old style load binder.

The invention has other objects and advantages which will become apparent from the following description of one embodiment of the invention shown in the accompanying drawings forming a part of this specification, said embodiment corresponding to the form of Figs. 1-5 of the aforesaid patent. As the description proceeds, it will be clear that the improvements are also applicable to the form of Figs. 6, 7 and 8 of the patent.

In said drawings,

Fig. 1 is a sectional elevation of the drum and part of the lever of my improved load binder;

Fig. 2 is an elevation on a smaller scale showing the improved load binder just as the lever is about to be swung to tighten the load, part of the lever being omitted;

2

Fig. 3 is a fragmentary elevation showing the load binder after the lever has been swung as far as possible, most of the lever being omitted;

Fig. 4 is an elevation of the preferred locking pin, which may be used when the load binder is self-locked as in Fig. 3; and

Fig. 5 is a fragmentary plan view of the drum looking at the edges of the two rockers.

Referring particularly to the drawings, my improved load binder consists of a lever 10, which is preferably a steel forging, integral with a hollow drum 11 on which a chain is wound, as will be described, said drum having a central opening 12 to save weight without sacrificing strength. The drum is not circular, as in my aforesaid patent, but is more or less oval with the long axis of the oval approximately aligned with the lever; and the shape of the opening 12 conforms to that of the drum, so that the radial thickness of the drum is substantially the same all around, thus obviating any zone of weakness. Integral with the drum are two flanges 13 which are spaced far enough apart to receive between them the chain 20 to be described, and which act as chain guides when the chain is wrapped around the drum. The flanges 13 extend about half way around the drum and are made thicker on the inside, as indicated at 13a, Fig. 1, to prevent the entire chain from entering, that is, the rivets 20a of the chain can not lie between the flanges. The chain rides on the periphery of the drum at all times when tightened. The result is that the chain is guided along the center line of the drum and will be prevented from climbing on the outer edges of the flanges, and as soon as slack is taken up in the chain it will stay put. Rockers 14 are integral with flanges 13 and also serve as attaching ears for a clevis 15 pivoted at one end to the rockers by a pivot pin 16 passed through a bore 16a in each rocker. Unlike the rockers of the aforesaid patent, the rockers 14 are symmetrical relative to the axis of bore 16a. Clevis 15 embraces the drum and the end of the lever 10 where it joins the drum, and permits the drum to pass through it when the load binder is tightened, as a comparison of Figs. 2 and 3 will make clear. An eye 17 is swiveled to the free end of the clevis, and chain link 18 connects the eye 17 with a hook 19, preferably by means of another eye. Hook 19 is of course attached to one end of a load-binding chain (not shown) or similar flexible binding element which passes partly or entirely around the load (not shown) on the truck body, sled, skid or other vehicle.

A flat link chain 20 is shown as attached to the drum 11 by means of a link 21 which is pref-

erably similar to each of the links of chain 20. Link 21 is permanently pivoted upon the drum by means of a pin 22. The flanges 13 are widened to provide attaching ears 23, Fig. 1, to accommodate the pivoted end of link 21, and the oval shape of the drum is modified as at 12a to provide an inwardly directed projection giving adequate strength near where the load is applied. The periphery of the drum is shaped as at 24 to conform to link 21. Pin 22 is wholly within the confines of the drum, which causes link 21 to be mostly within the confines of the drum. A pin 25 connects chain 20 permanently or otherwise to link 21. The other end of chain 20 may be secured to the load-binding chain in any desired way. The groove formed by the periphery of the drum and the flanges 13 is smooth throughout, which is of importance in manufacturing the device. Chain 20 constitutes a flexible non-stretching member, and as explained in the aforesaid patent it may be superseded by a cable or similar member.

The load binder tightens the load by swinging lever 10 from the position of Fig. 2 to that of Fig. 3, as already stated. With the parts in the position of Fig. 3, the load binder is locked, and any pull exerted by the load on the load-binding chain will tend to swing lever 10 downwardly or toward the load, or in other words, the load itself will tighten the described load binder. The self-locking action of the load binder is more fully explained in the aforesaid patent. As trucks frequently traverse rough roads, and swing at high speed around curves, the described load binder even though locked normally may tend to unlock due to the momentum or inertia of the heavy lever. To prevent any possibility of such unlocking, the clevis 15 has two small aligned bores 26 through which a cotter pin 27 may be thrust when the parts are in the position of Fig. 3. Cotter pin 27 preferably has its small end slightly enlarged as shown to prevent it from working out of the bores 26, yet permitting it to be withdrawn manually. The advantages of this locking arrangement are its simplicity and effectiveness. No additional material is required on the drum, and the lever can not move even slightly toward unlocking position because the cotter pin when in bores 26 directly engages the chain 20 where wrapped around the drum, and interlocks with the edges of the chain links. Thus when the load settles, which makes slack in the load-binding chain, the described load binder will remain attached and can not unlock, nor can the lever constantly swing toward unlocking position and thus wear out the locking pin.

It is difficult to visualize the advantages of the described drum but actual tests with a 76 lb. weight as the load, and readings on scales attached to the lever in each case at the same distance from the center of the trunnions, prove conclusively that the described drum is an important improvement. These tests may be summarized as follows:

My Patented Load Binder (take-up, 4 5/8 in.)

At start	1/4	3/2	3/4
20 lb.	16 lb.	8 lb.	zero

Present Load Binder (take-up, 5 7/8 in.)

20 lb.	16 lb.	10 lb.	6 lb.

Old Style Load Binder (take-up, 4 3/8 in.)

18 lb.	17 lb.	14 lb.	8 lb.

Thus it is clear that my improved load binder has a more uniform application of energy to the

lever than in the patented load binder and has a greater take-up. As compared with the old style load binder the take-up is far greater and the application of energy, except at the start, is materially less. It should be particularly noticed that I attain these results without sacrificing any of the important advantages of the patented load binder.

Referring to Fig. 5, it will be observed that the rockers 14 are thickened as at 14a. This increases the strength of these projecting parts. As the parts are viewed in Fig. 1, bore 16a is about 5° to the left of the axis, shown in dot and dash lines, which passes through the center of pivot pin 22 and through the center of bore 16a. The location of bore 16a in the manner shown helps to hold the load binder in locked position, especially if the load-binding chain should get a little slack. Note too that the greater portion of the drum is to the left of the pivot pin 16, and that the lower part of the drum (as viewed in Fig. 1) and the pivot 22 are brought closer to the center line. Thus the ears 19 of the patent are practically eliminated, which obviates interference caused by loose material getting in between said ears and the clevis.

I contemplate making the drum and lever assembly in two forged parts, each consisting of one-half of the drum and one-half of the lever, and then welding the two halves together. This is believed to be less expensive than to forge the entire assembly and afterwards machine it to form the groove around the drum, in which the chain 20 wraps.

Having described my improvements, what I claim as new and desire to secure by Letters Patent is:

1. A load binder of the type which comprises a lever rigidly secured at one end to a drum, a rigid element pivotally connected at one end to the drum at a point outside the periphery of the drum and having means at the other end facilitating attachment to a load-binding chain, and a flexible non-stretching element attached at one end to the drum at a point substantially on the opposite side of the drum from the point of connection of the rigid member and adapted to be wrapped around the periphery of the drum when the load binder is tightened; that improvement which consists in making the drum generally oval, with the long axis of the oval substantially aligned with the axis of the lever and the major portion of the drum being disposed on one side of the plane lying at right angles to the general plane of the load binder and intersecting the points of attachment of the rigid member and the flexible non-stretching element, said lever being disposed on the opposite side of said plane.

2. A load binder of the type which comprises a lever rigidly attached to a drum, a pair of rockers integral with the drum, a rigid member pivoted at one end to the rockers outside the periphery of the drum, a flexible non-stretching element attached at one end to the drum substantially on the opposite side thereof from the pivotal attachment of the rigid member, said flexible non-stretching element being adapted to be wrapped around the periphery of the drum when the load binder is tightened; that improvement which consists in making the drum oval-shaped and forming each of the two rockers so as to be symmetrical on opposite sides of the plane lying at right angles to the general plane of the load binder and passing through the point of attachment of the flexible element and the pivot axis of the rigid member, said plane being

approximately 5° from the plane which passes through the point of attachment of the flexible elements and is at right angles to the long axis of the oval of the drum, said first-mentioned plane being on the opposite side of the last mentioned plane from the lever.

3. A self-locking load binder of the type which consists of a lever rigidly attached at one end to a hollow drum, a pair of rockers integral with the drum, a rigid member pivoted at one end to the rockers outside the periphery of the drum, a chain attached at one end to the drum on the opposite side thereof from the pivot attachment of the rigid member, said chain being adapted to be wrapped around the periphery of the drum when the load binder is tightened; that improvement which consists in providing a transverse bore in the rigid member near the pivot connection thereof and a locking pin fitting said trans-

5

verse bore, said locking pin engaging the chain where wrapped around the drum and preventing any movement of the lever toward unlocking position.
